UNITED STATES PATENT OFFICE.

ROSCOE C. PFLEAGER, OF CLEVELAND, OHIO, ASSIGNOR TO BENJAMIN F. KLEIN, OF CLEVELAND, OHIO.

DESIGN FOR A BRACKET BACK FOR LIGHTING FIXTURES.

Application filed December 2, 1925. Serial No. 15,601. Term of patent 3½ years.

To all whom it may concern:

Be it known that I, Roscoe C. Pfleager, a citizen of the United States, residing in Cleveland, in the county of Cuyahoga and State of Ohio, have invented a new, original, and ornamental Design for a Bracket Back for Lighting Fixtures, of which the following is a specification, reference being had to the accompanying drawing, forming part thereof.

The figure is an elevation of a bracket back displaying my new design.

I claim:

The ornamental design for a bracket back for lighting fixtures, substantially as shown.

Signed my me, this 27th day of November, 1925.

ROSCOE C. PFLEAGER.
